Primary Examiner — Anhdao Doan(74) *Attorney, Agent, or Firm* — McAndrews, Held & Malloy, Ltd.(57) **CLAIM**

The ornamental design for an analyte sensor device, as shown and described.

DESCRIPTION

FIG. 1 is a front perspective view of an analyte sensor device with an environment;

FIG. 2 is a front perspective view thereof;

FIG. 3 is an enlarged front perspective view of area 3 of FIG. 2;

FIG. 4 is a top plan view thereof;

FIG. 5 is a bottom plan view thereof;

FIG. 6 is a front view thereof;

FIG. 7 is a left side view thereof;

FIG. 8 is a right side view thereof; and,

FIG. 9 is a rear view thereof.

The broken lines immediately adjacent the shaded areas represent the bounds of the claim, and the remaining broken lines are directed to environment and are for illustrative purposes only; the broken lines form no part of the claimed design.
